DESIGN FOR A SMOKING STAND

Alfred H. Sander, Maplewood, N. J., and Elon G. Pratt, New York, N. Y., assignors to Smokador Manufacturing Co., Inc., Bloomfield, N. J., a corporation of Delaware

Application August 6, 1935, Serial No. 57,979

Term of patent 3½ years

To all whom it may concern:

Be it known that we, Alfred H. Sander and Elon G. Pratt, citizens of the United States, residing, respectively, in Maplewood, New Jersey, and the city of New York (Borough of Manhattan), State of New York, have invented a new, original, and ornamental Design for a Smoking Stand, of which the following is a specification, reference being had to the accompanying drawing, forming part thereof, in which

The figure is a perspective view of a smoking stand, showing our new design.

We claim:

The ornamental design for a smoking stand, substantially as shown.

ALFRED H. SANDER.
ELON G. PRATT.
